(57) **CLAIM**

The ornamental design for the beverage container support rack, as shown and described.

DESCRIPTION

FIG. 1 is a perspective view of a beverage container support rack;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof;

FIG. 7 is a bottom plan view thereof;

FIG. 8 is a perspective view of a beverage container support rack according to another embodiment;

FIG. 9 is a front elevation view of the beverage container support rack of FIG. 8;

FIG. 10 is a rear elevation view of the beverage container support rack of FIG. 8;

FIG. 11 is a left elevation view of the beverage container support rack of FIG. 8;

FIG. 12 is a right elevation view of the beverage container support rack of FIG. 8;

FIG. 13 is a top plan view of the beverage container support rack of FIG. 8; and,

FIG. 14 is a bottom plan view of the beverage container support rack of FIG. 8.

The broken lines in the drawings illustrate portions of the beverage container support rack which form no part of the claimed design.
